UNITED STATES PATENT OFFICE.

CARL HEINRICH JULIUS WIESE, OF HAMBURG, GERMANY.

WATER-WHEEL.

SPECIFICATION forming part of Letters Patent No. 643,176, dated February 13, 1900.

Application filed March 5, 1898. Serial No. 672,772. (No model.)

To all whom it may concern:

Be it known that I, CARL HEINRICH JULIUS WIESE, a citizen of free city of Hamburg, residing at Hamburg, in the Empire of Germany, have invented certain new and useful Improvements in Water-Wheels, (for which I have applied for patents in England, dated February 2, 1898, No. 2,707; in Austria, dated February 4, 1898; in Hungary, dated February 5, 1898, No. 1,753; in Germany, dated January 29, 1898; in France, dated February 2, 1898, No. 262,428; in Belgium, dated February 1, 1898, No. 104,049; in Sweden, dated January 31, 1898, No. 165; in Norway, dated February 4, 1898, No. 9,437, and in Switzerland, dated February 2, 1898, No. 17,622,) of which the following is a specification.

The present invention relates to a water-wheel which is designed to utilize the motive force of flowing water without necessitating any artificial damming up of the water or requiring a vertical fall of water for its operation. The water-wheel may therefore be immersed direct in any stream which flows sufficiently fast to possess an appreciable amount of motive force.

In the accompanying drawings, in which the water-wheel is illustrated, Figure 1 is a top plan view of the wheel with the parts transmitting the power from the wheel-shaft omitted. Fig. 2 shows a vertical section of the wheel perpendicular to the direction of the stream.

Upon the vertical shaft *a*, which turns at its lower end in a step-bearing *n* and at its upper end in a bearing in a bracket *m*, fixed to a wall on the bank, are mounted a series of arms *c*, forming a wheel, which is connected to the shaft by a feather in such manner that the shaft must rotate with the wheel. The keyway being of considerable length, the wheel is free to rise and fall on the shaft as the water-level sinks or rises.

The wheel rests upon rollers *p*, running upon a circular rail *q*, fixed to the cover of a float *b*, loosely surrounding the shaft or axle *a*. As the water rises or falls so will the float ascend or descend, and with it the series of arms or wheel *c* resting upon it. On the ends of the arms are hung blades or paddles *g*, movable pivotally upon a vertical bolt *e*. A horizontal arm *f*, forged with the bolt, permits of

the blades hinged to it turning also in an upward direction. This latter movement is, however, limited to one direction only by a projection *r* on the hinges of the blades and stops *s* on the horizontal arms in such manner that the blades can only pass from a vertical to a horizontal position in the said direction.

The weight of the wheel *c* and the scoops *g* is so calculated that the lifting power of the float *b* allows of the complete immersion, or nearly so, of the blades when in a vertical position.

Supposing now the flow of the stream to be in the direction of the arrows, Fig. 1, one-half of the blades pendent from the arms *f* will be vertical, being prevented by the stops *s* from turning further by the stream. Through the resistance which the blades offer to the stream the series of arms are set in rotation. Assuming that at starting the position of the blades was at right angles to the direction of the stream at *u*, they will as they move onward remain parallel to each other, as the currents of the stream exert an equal pressure on both edges of the pivot-pins *e*, and the balance is therefore not disturbed. As soon, however, as the movement of the blades changes from one at right angles to the direction of the stream the lateral pressure begins to act.

The blades are then thrown out of equilibrium and, following the water-pressure, turn about the bolt *e*, as at *v*. They thus present their other sides to the current, and as the stops *r* in this position do not prevent their turning on the hinge-arm *f* the blades lie flat on the water and offer no appreciable resistance thereto. When the position of the blades is again vertical to the direction of the stream, as at *w*, the reverse action takes place, the blades turn to their vertical position, and, with their original sides to the stream, they again offer resistance to the water.

Chains *i* are provided for preventing the blades from turning too far at the points *v* and *w*. The shaft *a* is thus on the rotation of the wheel *c* carried around with it and transmits its power through bevel-wheels *y* to a shaft *z*.

What I claim, and desire to secure by Letters Patent of the United States, is—

A wheel for utilizing the power of flowing

water without the use of natural or artificial dams, comprising a series of radial arms in a horizontal plane, each arm provided, at its outer extremity, with a bucket or blade, the 5 same being hinged to the arm by means of a horizontal shaft *f*, the said shaft being provided with a vertical pin *e*, entering and turning freely in the end of the arm, whereby the

bucket may swing in the two directions described.

In testimony whereof I have hereunto set my hand in the presence of two witnesses.

CARL HEINRICH JULIUS WIESE.
